UNITED STATES PATENT OFFICE.

CASPER SCHAEFER, OF CAMBRIDGE CITY, INDIANA.

DESIGN FOR A GAS-STOVE.

No. 38,304.

Specification for Design.

Patented Oct. 30, 1906.

Application filed September 14, 1906. Serial No. 334,679. Term of patent 7 years.

To all whom it may concern:

Be it known that I, CASPER SCHAEFER, a citizen of the United States, and a resident of Cambridge City, in the county of Wayne and State of Indiana, have invented a new, original, and ornamental Design for a Gas-Stove, reference being had to the accompanying drawing, in which the figure is a perspective view of a gas-stove, showing my design.

I claim—

The ornamental design for a gas-stove as shown.

CASPER SCHAEFER.
